[57] CLAIM

The ornamental design for a hose nozzle, as shown and described.

DESCRIPTION

FIG. 1 is a perspective view taken from the top, front and right side of a hose nozzle showing my new design; FIG. 2 is a right side elevational view thereof, the left side being a mirror image of right side shown; FIG. 3 is a front elevational view thereof; FIG. 4 is a rear elevational view thereof; FIG. 5 is a top plan view thereof; and FIG. 6 is a bottom plan view thereof.

The fragmentary broken line illustration of a human hand, a hose and water spray in FIG. 1 is for purposes of illustration only and forms no part of the claimed design.
